UNITED STATES PATENT OFFICE.

JAMES A. HERRICK, OF NEW YORK, N. Y.

GAS-PRODUCER.

1,001,398.

Specification of Letters Patent. Patented Aug. 22, 1911.

Application filed March 30, 1909. Serial No. 486,825.

To all whom it may concern:

Be it known that I, JAMES A. HERRICK, residing at New York, in the county of New York and State of New York, have invented certain new and useful Improvements in Gas-Producers, of which the following is a specification.

This invention relates to the manufacture of producer gas and one of the objects therefore is to provide a new and improved producer.

Another object is to provide apparatus of the above character wherein the mass will be kept from clogging and the formation of crevices and fissures prevented.

Another object is to provide apparatus wherein producer gas of a calorific quality will be generated.

Other objects will be in part obvious and in part pointed out hereinafter.

The invention accordingly consists in features of construction, combinations of elements and arrangement of parts, which will be exemplified in the construction herein-after described, and the scope of the application of which will be indicated in the following claims.

In the accompanying drawings wherein is illustrated one of various embodiments of my invention: Figure 1 is a vertical, sectional view taken through the producer; Fig. 2 is a horizontal section taken on the line 2—2 of Fig. 1; and Fig. 3 is a similar view taken on the line 3—3 of Fig. 1.

Similar reference characters refer to similar parts throughout the several views of the drawing.

Referring now to the drawings A represents the body of the producer the same being constituted, in the present instance, by upper and lower sections 2 and 3, respectively, the upper section being supported as by means of legs 4 and struts 5. The producer is divided horizontally to provide the upper and lower sections 2 and 3 along the line indicated at 6 which construction permits of the lower section 3 being revolved. This section is mounted upon a circular track 7 and has wheels 8 adapted to traverse said track.

The means provided for revolving section 3 comprises gear wheel 10 mounted upon the shaft 11 driven by means of a pulley and belt 12 and 13 respectively, the latter receiving its power from any suitable source. Gear wheel 10 meshes with peripheral teeth

14 carried externally of the revoluble section.

In order to prevent the escape of gas from between sections 2 and 3 a water seal 15 is provided.

16 denotes a basin or receptacle formed underneath the body of the producer into which depends a tapering end 17 of section 3. The lower edge of the latter extends below the level of the water in the basin whereby the lower end of the producer is trapped or sealed. The lower end 17 of the section 3 and the basin 16 constitute ash receptacles and the ashes may be removed from the basin by any suitable means, Archimedean screws 18 being provided for this purpose in the present embodiment of the invention. These screws may be revolved as by means of pulleys 20 whereupon the screws will deliver the ashes upon a traveling belt 21 which carries them from the producer.

Located centrally of the lower portion 17 of section 3 are twyer boxes 22. The twyer boxes 22 radiate from a central box 23 which receives the blast from a vertical portion 24 of a blast pipe 25 which extends upward through the lower end of the producer. The roofs of the twyer boxes are sloped as shown so that ashes in the lower portion of the producer will readily pass downward therethrough. Located upon the ends of these twyer boxes is a bracket 26 which has a curved portion 27 which when section 3 is revolved will engage clinkers or other hard formations, thereby assisting in a prevention of clogging of the apparatus.

28 represents a spiral flange positioned exteriorly of section 24 of the blast pipe, said flange operating to feed ashes in a downward direction during the revolution of section 3.

The upper portion or section 2 of the producer is provided with an arched roof 30 formed of bricks embedded in metal and formed centrally of the roofed portion is an aperture through which extends a revoluble chute 31. This chute is carried upon a shaft 32 extending upward centrally of the hopper 33 resting upon the roof portion 30 of the producer, the upper end of the shaft passing through the cover 34 of the hopper and having upon its upper end a bevel gear 35. Meshing with bevel gear 35 is a similar gear 36 upon horizontal shaft 37 supported in suitable journals 38 in a

bracket 39 carried by the hopper and this shaft has a second bevel gear 40 thereon which meshes with similar gear 41 carried by the shaft 11. Shaft 11 is supported by 5 means of a suitable thrust bearing 42 carried upon the bracket 43 mounted upon the upright 4. Shaft 32 is provided with a plurality of laterally extending members 44 which are positioned between radially extending members 45 upon the inner wall of 10 the hopper. These members coöperate during the rotation of shaft 32 to stir the fuel in the hopper and prevent any clogging thereof. Shaft 32 also carries a pierced 15 plate 46 mounted in a recess 47 formed in hopper 33, said plate coöperating to support the shaft and, the apertures 48 of this plate are adapted to register with corresponding apertures 50 of the plate 51 carried by the lower end of the hopper. When 20 these apertures are in registry the coal falls into chute 31 and when they are out of registry the chute is closed. A funnel 51' may be employed for discharging fuel from the 25 hopper and the damper 52 to close communication between the funnel and the hopper.

Located within section 2 of the producer, in the present instance, is a depending annular curtain or partition 53, the lower end 30 of which terminates slightly above the point of jointure of sections 2 and 3. The annular wall of this partition or curtain is spaced from the inner walls of section 2 of the producer to form a mixing chamber 54. The 35 partition 53 is supported at its lower end by means of projecting member 55 which extends laterally from the inner walls of section 2 of the producer. Vertically extending members or webs 56 are provided between 40 the exterior wall of the partition and the inner wall of section 2, said webs being integrally or otherwise connected with said walls thereby forming an additional support for the partition. Partition 53 at its lower 45 portion is provided with arched shaped recesses 57 so that gases passing downward therethrough may freely pass upward into the space provided between the exterior wall thereof and the inner wall of section 2 of 50 the producer.

The blast pipe 25 which, as shown, extends downward in a vertical direction adjacent the producer is provided with a branch 58 which leads into the space within the annular partition 53, said passage way being suitably valved as at 60. It will be understood 55 that blast pipe 25 may be connected with a suitable source of air supply or that any other gas may be discharged therethrough 60 into the interior of the producer.

61 and 62 respectively indicate blowers or inspirators. The blower 61 being located preferably opposite branch pipe 58 and the blower 62 being located near the lower end 65 of the blast pipe which is provided with a

valve 63 intermediate said blowers. The blowers in the present instance are of that class which are actuated by a steam jet so that a proper admixture of steam and air may be discharged into the producer. 70

64 and 65 respectively indicate steam pipes which lead into the blowers, said pipes being adapted to receive steam from a feed pipe 66, in turn receiving its supply from a suitable source. Surrounding the annular 75 partition 53 at its upper portion is a correspondingly shaped space 67 from which leads a gas discharge conduit 68.

Having thus described the construction of this embodiment of my invention the operation thereof, which to a large extent will be obvious is as follows: The carbonaceous material in the present instance bituminous coal is introduced into the hopper 53 and discharged by chute 31 into the interior 80 of the producer, whence it falls into the combustion chamber constituted by the lower portion of section 3. The fuel is then lighted in the usual manner. When a suitable bed of burning fuel has been obtained 85 within the producer additional fresh fuel is introduced by means of the hopper and the apparatus is then ready to operate. When the apparatus is in normal operation the lower section 3 is revolved as has been heretofore explained, the various dampers in the blast pipe being regulated to admit the proper amount of air or steam or an admixture of these gases into the interior of the producer. The air or steam passing through 90 the branch pipe 58 above the bed of fuel within the space interiorly of partition 53 which may be termed "retort" then passes in a downward direction to meet the gases passing upward through the lower section 3 95 which may be termed "a combustion chamber." The gases thereupon pass upward through the space provided between the exterior wall of the partition and the inner wall of section 2 of the producer which may 100 be termed a "mixing chamber." The gases are then discharged from the producer by 105 means of the discharge conduit 68.

It will accordingly be seen that I have provided a construction well adapted, among 110 others, to attain all the ends and objects of my invention in a simple though efficient manner. As the fuel in the retort becomes heated the more volatile hydrocarbon constituents thereof are distilled off and these 115 gases pass downwardly through a partly coked portion of the fuel, then they pass around the lower end of the partition 53 into the mixing chamber. These heavier hydrocarbon gases thereupon mix with the 120 lighter and more permanent gases which pass upward through the bed of fuel in the lower part of the producer. It will be noted that the distillation and oxidation of the 125 hydrocarbon constituents of the fuel will 130

take place in the retort and that the coke will be burned off in the lower portion thereof, sufficient oxygen being supplied by the blast to oxidize any volatile constituent remaining in the fuel present in that portion of the producer. The carbon dioxide gas passing upward through the coked material unites largely with the free carbon present to form carbon monoxide gas and any carbon monoxide gas formed in the lower portion of the producer of course will pass through the bed to the mixing chamber unchanged. Should it be desired to cool the mass or any portion thereof or to furnish gas rich with hydrogen, steam may be discharged from the twyer boxes into the lower section 3 of the producer and the hydrogen formed by the disposition of the steam will of course pass unchanged through the mass 20 into the mixing chamber.

One important advantage attained by reason of the present construction resides in the fact that the fuel being introduced cool at the top of the producer is gradually heated before arriving at the seat of combustion, and accordingly the loading of the apparatus with fuel does not affect the continuity of the generation of gas. Another advantage attained herein is the prevention of the lighter carbon gases from straining upward through the bed meeting free air in the retort and burning locally, thereby tending to ignite the heavier hydrocarbon gases and forming combustion cavities in the body of the bed. Another important advantage accruing herein is that the revolution of the lower portion of the producer tends to prevent any clogging or choking of the fuel within the producer and insures a steady 40 progress of the mass from the time the fuel is introduced into the retort until the ashes are discharged from the lower end of the producer.

While I have shown the depending curtain of annular form and disposed centrally of the producer, it will be obvious that its shape may be changed or that it may be differently located within the producer.

As many changes could be made in the above construction and many apparently widely different embodiments of this invention could be made without departing from the scope thereof, it is intended that all matter contained in the above description or

shown in the accompanying drawings shall 55 be interpreted as illustrative and not in a limiting sense. It is also to be understood that the language used in the following claims is intended to cover all of the generic and specific features of the invention herein 60 described and all statements of the scope of the invention which as a matter of language, might be said to fall therebetween.

Having described my invention what I claim as new and desire to secure by Letters 65 Patent is:

1. The combination in a gas producer of a casing comprising a fixed upper section and a revoluble lower section, said upper section having a depending annular curtain 70 spaced from the walls thereof and terminating adjacent the point of jointure of said sections, means for delivering a blast within said annular curtain and also into the lower section of the producer, and means for discharging gases from the space between said annular curtain and the wall of said upper section. 75

2. The combination in a gas producer, of a casing comprising an upper fixed section 80 and a lower movable section, a twyer box in the lower section, a support for said twyer box, and means on said support for forcing the ashes downward when the lower section is revolved. 85

3. The combination in a gas producer, of a casing comprising upper and lower sections, the latter of which is revoluble, a twyer box having outstanding legs, means carried by said legs for engaging and crushing clinkers or other hard formations in the mass, a support for the twyer box, and means on said support which tends to force the ashes downward during the revolution of said lower section. 90 95

4. The combination in a gas producer, of a casing comprising upper and lower sections, a stationary twyer box in said lower sections, a support for the twyer box, and a spiral arranged upon said support which is 100 adapted to force the ashes downward during the revolution of the twyer box.

In witness whereof I affix my signature in the presence of two witnesses.

JAMES A. HERRICK.
